CLAIM

The ornamental design for a display panel or portion thereof
with graphical user interface, as shown and described.

DESCRIPTION

FIG. 1 is a front view of a display panel or portion thereof
with graphical user interface showing our new design; and,
FIG. 2 is a front view thereof showing environmental matter.
The dot-dash broken lines in FIG. 1 illustrate a display panel
or portion thereof and form no part of the claimed design.
The dash-dash broken lines on the display panel represent
portions of the graphical user interface that form no part of
the claimed design. The dot-dash broken lines in FIG. 2
showing a display device illustrate environmental matter
that forms no part of the claimed design.
